(57) CLAIM

I claim the ornamental design for a display screen or portion thereof with graphical user interface, as shown and described.

DESCRIPTION

FIG. 1 is a front view of a display screen or portion thereof with graphical user interface;

FIG. 2 is a front view of another embodiment of the display screen or portion thereof with graphical user interface;

FIG. 3 is a front view of another embodiment of the display screen or portion thereof with graphical user interface; and, FIG. 4 is a front view of another embodiment of the display screen or portion thereof with graphical user interface.

The broken lines in FIGS. 1-4 showing the display screen are for environmental purposes form no part of the claimed design.

The broken lines in FIGS. 1-4 depicting text/words, numbers, symbols and other shapes in the graphical user interface form no part of the claimed design.

1 Claim, 4 Drawing Sheets

The image shows a screenshot of a medical insurance plan overview page. At the top, there's a navigation bar with a 'Back' button. The main title is 'Medical Insurance'. Below that, a sub-section title is 'Select Your Medical Plan'. To the right, there are buttons for 'DAYS LEFT TO ENROLL', '$2,123 PER PAYCHECK', 'COMPARE PLANS', 'VIEW DETAILS', and 'ESTIMATE COSTS'. The main content area is titled 'Freedom Choice High Deductible with HSA'. It features a 'SHOW COSTS FOR' dropdown set to 'Employee'. Below this, there's a 'AT-A-GLANCE' section with a 'Employee' benefit listed. A 'DOCTOR ACCESS' section follows, stating that provider access is through the plan's network. A 'Need referred for a specialist?' section is present. At the bottom, there's a 'Search for Provider' input field and a 'I don't want this benefit.' checkbox. On the right, there's a 'Share Plans' button and an 'ENROLL IN THIS PLAN' button.
